UNITED STATES PATENT OFFICE.

STEPHEN WILSON, OF PHILADELPHIA, PENNSYLVANIA, ASSIGNOR TO
WALTER PINCUS, OF SAME PLACE.

CAR-STRAP.

SPECIFICATION forming part of Letters Patent No. 537,659, dated April 16, 1895.

Application filed January 4, 1895. Serial No. 533,817. (No model.)

To all whom it may concern:

Be it known that I, STEPHEN WILSON, a citizen of the United States, residing in the city and county of Philadelphia and State of Pennsylvania, have invented certain new and useful Improvements in Car-Straps, of which the following is a full, clear, and exact description, reference being had to the accompanying drawings, forming a part of this specification.

The nature of my invention is a car-strap or hand-hold device, which, as generally stated, comprises a strap or flexible member with depending ends, one of which ends is provided with a weight or hand-hold that drops by gravity to maintain the other end of the strap normally raised, which latter end constitutes an extensible hand-hold, that is to say, such latter end may be readily grasped and drawn downward against the action of the weighted portion, as will hereinafter appear.

In the drawings, Figure 1 is a side elevation of my improved car-strap, the full lines showing it in its normal position, and the dotted lines showing it as extended. Fig. 2 is an end view thereof. Fig. 3 is an elevation of the weight hand-hold detached. Fig. 4 is a transverse section, as on the line $x-x$ of Fig. 3.

30 A designates a strap, or other suitable flexible device, which runs freely through an appropriate hanger B suspended from the usual supporting bar C within the car; or the strap may run directly over the bar if desired. One of the depending ends of the strap is passed through and secured to an upwardly projecting eye e on a ring or hand-hold E, while the other end of the strap is extended freely through the eye and is looped to form a hand-hold F. Between the free end of the looped portion and the body of the strap there is interposed a loop g, of leather or the like, which constitutes a stop to limit the downward movement of the hand-hold E, the latter being of sufficient weight to drop to the stop by gravity and thus maintain the looped hand-hold normally raised. The weight hand hold is within the reach of a person of ordinary

height, by whom it may be used. When the looped hand-hold is grasped, the hand-hold 50 E is drawn up, in which case the strap is extended to accommodate a person of short stature. When the looped-hand hold is released the parts automatically resume their original positions. 55

I claim as my invention—

1. A car-strap or hand-hold device, consisting in the combination, with the supporting bar, of a looped flexible member freely connected therewith so as to have two depending 60 oppositely-movable ends which constitute hand-holds, one of said ends being weighted to maintain the other end normally raised, substantially as described.

2. A car-strap or hand-hold device, comprising a looped flexible member, one depending end thereof constituting an extensible hand-hold, and the other depending end thereof being provided with a weight hand-hold which maintains the first-named hand-hold normally raised, substantially as described. 70

3. A car-strap or hand-hold device, comprising a looped flexible member, with two depending oppositely-movable ends, and a 75 weight and hand ring provided with an eye to which one end of the strap is secured, and through which the other end of the strap extends, said extending portion being provided with a stop, substantially as described. 80

4. A car-strap or hand-hold device, consisting in the combination with the supporting bar and a depending hanger thereon, of a looped strap extending freely through said hanger, and a weight hand-hold secured to 85 one depending end of the strap so as to maintain the other depending end thereof normally raised, substantially as described.

In testimony whereof I have hereunto affixed my signature in the presence of two 90 subscribing witnesses.

STEPHEN WILSON.
